HYDROMECHANICAL PRESS

William Klocke, Woodhaven, N. Y.

Application May 14, 1935, Serial No. 21,322

10 Claims. (Cl. 100—70)

This invention relates to hydromechanical presses.

The invention provides presses in which the hydraulic principle of operating a tool-carrying reciprocating slide may be effectively applied to the actuation of elongated slides (length much greater than width), and to the actuation of slides on which the reactions during the work which is performed by the forming parts, are unsymmetrical, as for example where such reactions are of greatest magnitude at one corner or side of the slide.

The invention provides presses in which the hydraulic principle may be effectively applied to the actuation of reciprocating slides, in such manner that the driving force is applied to the slide at four points (similar to the application of the driving force to the slides of large mechanical presses), and also in such manner that the slide cannot cant under the effects of unsymmetrical work-reactions.

The invention further provides presses embodying the hydraulic principle, in which the reciprocating slide has a definite bottom-of-the-stroke position, beyond which the force developed within hydraulic motors cannot be exerted between the crown and bed, and the press-frame thereby protected from the damaging effects of excessive pressure built up in or by the hydraulic motors.

The invention further enables presses to be built of a size equalling and exceeding that of the largest mechanical presses, and operating with equal or greater speed than such mechanical presses, at a considerable saving of cost.

The invention further provides a press embodying a plurality of hydraulic motors having reciprocating pistons for driving a reciprocating slide having the advantages and improvement of an equalized action of the several pistons on the slide.

Two embodiments of the invention are illustrated in the accompanying drawings, wherein:

Fig. 1 is a view in elevation (with certain parts in section) of a press according to one embodiment of the invention, the press being viewed from the front.

Fig. 2 is a transverse sectional view on the line 2—2, Fig. 1, looking in the direction of the arrows.

Fig. 3 is a view similar to Fig. 1 of a second embodiment.

Fig. 4 is a transverse sectional view on the line 4—4, Fig. 3, looking in the direction of the arrows.

Referring to said drawings, numeral 10 designates the frame of a press, comprising the side members 11 and 12, a bed 13 and a crown 14 extending across the press from side to side. In the type of frame shown, the bed and crown 13 and 14 and the side members 11 and 12 are tied together by the usual tie-rods 15.

Numeral 17 designates a reciprocating slide. As is well understood, the forming tools of the press are mounted on the bed 13 and slide 17.

The slides 17, as herein shown, are of large area. The slides of large presses are also usually elongated, as here shown, the length of the slides from side to side of the press, being considerably greater than the width of the slide from front to rear of the press. In large presses the span or distance between the side frames amounts to fourteen feet and more. In presses where the area of the slide is large, and especially in elongated slides, the greatest resistance offered by the forming tools which are mounted on the bed and slide, during the forming operation, is in many instances unsymmetrical with relation to the major and minor axes of the slide, the point or location of the greatest resistance often being at one side or at one corner of the slide.

In presses having slides of large area, the slide is usually actuated by a crank-shaft running across the press from side to side which is connected to the slide by connecting or pitman rods 30 at each side of the minor axis of the slide. Lately large presses have been built with two crank shafts running from side to side of the press and having connections to the slide on either side of the minor axis of the slide and also on either side 35 of the major axis of the slide. With such presses having two crank-shafts running from side to side of the press, the mechanism becomes complicated, crowds the space at the top of the press, necessitates the employment of heavier crowns, 40 and adds very considerably to the cost of the press. The "four point" connection of the actuating means to the slide however has the advantage that the tendency of the slide to cant when the resistance which is transmitted to the 45 slide by the forming tools is unsymmetrical, is counteracted.

According to the present invention, hydromechanical means 20 (20' Figs. 3 and 4) are provided for actuating (reciprocating) the slide 17. 50 The hydromechanical means comprises a plurality of hydraulic motors together with mechanical means for equalizing the action of the hydraulic motors in imparting movement to the slide, and the slide actuating mechanism com- 55

prising said plurality of hydraulic motors is such that the driving force of said motors is transmitted to the slide at a plurality of points or locations, such points or locations being on either side of one axis of the slide, and preferably on either side of two axes of the slide adjacent the four corners thereof.

Referring to Figs. 1 and 2, numerals 22 and 23 designate two hydraulic motors. The hydraulic 10 motors preferably each comprises a hydraulic piston and a cylinder. In the form of embodiment shown the structure is simplified, two pistons 25 and 26, working in a common cylinder 28 being provided. The pistons 25, 26 are opposed pistons and reciprocate in each end or side of the cylinder 28 in opposite directions. The 15 hydraulic motors 22, 23 are preferably mounted on the crown of the press, as indicated at 30, between the side members 11 and 12, and the arrangement is such that the force of the pistons acts crosswise of the press, parallel to the crown 14, and the crown 14 in this form of embodiment is constructed primarily as a tension element, rather than a compression element or arch. 20 The pistons 25, 26 each have rods 31, which extend through stuffing boxes 33 at the ends of the cylinders or cylinder 28.

Driving connections 36, 37 are provided between the slide 17 and each of the piston-rods 31. 30 The driving connections 36, 37 each preferably comprises a rock-shaft 40, extending across the press from front to rear, a lever arm 42, cross-head 44, a link 46 connecting the lever arm 42 and cross-head 44, and toggles connecting the 35 rock-shaft 40 and slide 17. Four of these toggles 50, 51, 52, 53 are preferably provided, the toggles consisting of lever arms 55, from the ends of each of the rock-shafts 40, and links 57, connected to each of the four lever arms 55. The four links 40, 57 are also preferably connected to the heads of four adjustable screws 59 preferably located at the four corners of the slide 17. The piston-rods 31, may be directly connected to each of the cross-heads 44, as here shown. The slide 17 is 45 guided in its movements by gibs 60.

Each of the rock-shafts 40 is preferably located adjacent the respective side members 11, 12 of the frame, and bearings 61 for said rock-shafts 40 are provided on the crown adjacent the ends of 50 the crown and near the tie-rods 15. With the bearings 61 thus located, the movement between the axes of the rock-shafts 40 and the center lines of the tie rods 15 is short, and the reaction of the toggles, 50, 51, 52, 53 on the bearings 61 55 of the rock-shafts 40 under the action of the forming tools, is transmitted almost directly to the tie-rods 15, and there is only a relatively slight strain produced in that part of the crown 14 between the bearings 61 of the rock-shafts 40 60 at each side of the press.

Guides 63, for each of the cross heads 44 may be provided. These guides may each rest at one end on a shelf 65 on each of the side members 11, 12 of the frame and be attached at their opposite 65 ends to the underside of the cylinder 28.

The faces of the pistons 25, 26 may be slightly inclined, as indicated at 68. The incline of the faces 68 is such that the force acting on the faces of the pistons 25, 26 has a component which 70 counterbalances or approximately counterbalances the weight of the piston, thereby avoiding unequal wear on the faces of the cylinders.

Numerals 70 designates the mechanical means which are provided hereby for equalizing the action of the hydraulic motors in imparting move-

ment to the slide 17. In the embodiment illustrated in Figs. 1 and 2, the aforesaid equalizing means 70 is partly combined with the structure of the driving connections 36, 37. The equalizing means 70 comprises connections between driving parts of the hydraulic motors and a common movable part capable of symmetrically receiving and transmitting driving force. In the embodiment illustrated in Figs. 1 and 2, numeral 73 designates a common movable part in the form of a disc 10 mounted to turn on a pin 75 projected from a fixed part of the press, as from a boss 77 on the underside of the cylinder 28, which cylinder as heretofore described is mounted on the crown 14 as indicated at 30. Each of the cross heads 44, 15 to which the piston rods 31 of each of the pistons 25, 26 are connected may be connected to the common part 73, as by means of links 80, 81. The links 80, 81 may each be connected to a pin 83 projecting from each of the cross heads, and to pins 85, 86 respectively, projecting from the common movable part 73.

When the pistons 25, 26 are driven apart, as by the admission of fluid under pressure through a port 89 to that part of the cylinder 28 in front 25 of the pistons, the cross heads 44 are likewise driven apart, rocking each of the shafts 40, and causing the arms of each of the toggles 50, 51, 52 and 53 to move into alignment, thereby driving the slide 17 toward the bed. As the arms of the 30 toggles approach alignment, the driving force of the pistons 25, 26 is very greatly augmented through the mechanical advantage obtained through the action of the toggles. By the mechanical principles here embodied, a very powerful driving force may be applied to the slide 17 by the pistons of the hydraulic motors, acting through the toggles 50, 51, 52 and 53, and much less powerful hydraulic motors may be employed than would be the case if the force 40 of the hydraulic motors were not augmented by the mechanical action of the toggles. The use of hydraulic motors in combination with the toggles has a further advantage that the pistons of smaller hydraulic motors may 45 be reciprocated more rapidly than the pistons of larger hydraulic motors, and with the present invention the presses may be operated with a rapidity equal to that of mechanical presses of equal size, and in the very large presses it is 50 contemplated rapidity of operation of the press can be obtained with greater advantage through the use of the present hydromechanical means for driving the slide actuating means than by the use of mechanical means for actuating the 55 slide.

The present combination of the hydraulic motors with the toggles has moreover a safety factor of very great value and importance. The toggles provide a definite limit to the bottom-of-the-stroke position of the slide. If the hydraulic motors should continue to drive the driving connections 36, 37 after the slide has reached its bottom-of-the-stroke position, the force of the hydraulic motors will not be further exerted 60 against the bed of the press (with the building up of stress between the slide and bed and with consequent strain on the frame) but such continued driving of the hydraulic motors would force the toggles out of alignment reversely, and 65 thereby relieve the stress between the slide and bed, in the same manner that the stress would be relieved by the reverse action of the hydraulic motors in raising the slide on the return stroke 70 of the slide in normal operation. 75

The return stroke of the slide 17 is effected by the mechanism described, on venting fluid through the port 89 and admitting fluid under pressure to the cylinders at the rear of the pistons.

Liquids, such as water or oil are usually employed for operating the hydraulic motors, but gaseous fluids such as air or steam could also be used.

If, on the working stroke, the forming tools mounted on the bed 13 and slide 17 encounter resistance by the work or material which is undergoing formation, which is greater on one side (with respect to either axis of the slide) than on the other, any tendency of the hydraulic motor acting on that side of the slide which encounters less resistance, to force that side ahead (cant the slide), is prevented by the equalizing means 70. Any tendency of one of the hydraulic motors, as for example, the hydraulic motor 23, to force the side of the slide 17 with which it is connected ahead of the side connected with the hydraulic motor 22, is checked, because any force tending to drive the piston 26 ahead of the piston 25 is immediately imparted to the piston 25 through the cross head 44 is connected to the piston 26, the link 81 and the common part or disc 73; and the turning of the common part 73 transmits to the piston 25 a force equal to that transmitted to it (common part 73) by the piston 26, such force being transmitted symmetrically through the link 80 and cross head 44 to which the piston 25 is connected. Through said equalizing means 70, therefore, the movement of the slide 17 on each side, and also the movement of the pistons 25, 26 by which each side of the slide 17 is driven, are equalized, and the slide 17 prevented from canting notwithstanding that the forming operation which is performed between the tools carried by the slide and the bed of the press may not be symmetrical, and in fact may be very unsymmetrical and concentrated at a side or corner of the press. With the four toggle connections shown, any tendency of the slide to cant at one corner is counteracted in the respective rock-shaft 40. That is, the toggle arms at each side of the press (as for example the toggles 52, 53) drive the slide on each corner equally, and the driving force transmitted from each hydraulic motor is imparted to the rock-shaft 40 and symmetrically applied by the rock-shaft to the toggles at its two ends.

Referring to Figs. 3 and 4, numerals 100, 101, 102 and 103 designate a plurality of four hydraulic motors. The hydraulic motors preferably each comprises a piston 105 and a cylinder 106, each of the pistons 105 has a piston rod 108 which extends outwardly through a stuffing box, and is connected to the slide 17 by a suitable attachment as indicated at 110. The piston rods, in this embodiment of the invention are directly attached to the slide. The four hydraulic motors 100-103, as here shown, are mounted on the crown 14 of the press, and preferably adjacent the side members 11, 12 of the frame, on either side of the major and minor axes of the crown, and likewise with respect to the slide 17, in such manner that the four piston rods 108 are connected to the slide 17, adjacent the four corners thereof. Gibs 110 may be provided for supplementing the piston rods 108 for guiding the reciprocating movement of the slide.

The mechanical means 70' for equalizing the action of the hydraulic motors in imparting movement to the slide 17, in this embodiment of the invention, comprises a common movable part 115

in the form of a rock-shaft 116 having oppositely extending arms 117, 118 thereon, and a linkage or connections between said arms 117, 118 and the slide 17 at four points or locations on the slide closely adjacent the places or locations where the four piston rods 108 are connected to the slide 17. The linkage is of such a character that it is capable of receiving and transmitting driving force from the hydraulic motors. As here shown, the aforesaid linkage comprises a pair of rock-shafts 120, 121, the rock shaft 120 being connected to the arm 117 of the common turning part 115 by an arm 123 and a link 124. Similarly the rock-shaft 121 is connected to the other arm 118 of the common turning part 115 by an arm 126 and a link 127. The rock-shaft 120 has a pair of arms 130, 131 thereon at each end, which arms are connected by links 133, 134 to the slide 17 at points or locations adjacent the points or locations where the piston rods 108 of the hydraulic motors 102, 103 are connected. Similarly, the rock-shaft 121 has arms 140, 141 at each end thereof, which arms are connected to the slide 17 at points or locations adjacent the points or locations where the piston rods 108 of the hydraulic motors 100, 101 are connected to the slide 17, by links 143, 144.

The common turning part 115 and the rock shafts 120, 121 are conveniently journaled in a bracket 150 and may be fastened upon the underside of the crown 14.

When fluid under pressure is admitted to the cylinders of the four hydraulic motors 100-103, in front of the pistons, the pistons are driven downwardly and move the slide 17 downwardly on its working stroke. The slide 17 moves evenly, because if there should be a tendency of any of the pistons of the four hydraulic motors to move ahead of the others, driving force will be transmitted from the piston of the motor which is tending to run ahead, through the mechanical symmetrically-acting equalizing means 70', to the pistons of the other hydraulic motors, the tendency counteracted and the action of the pistons equalized in imparting movement to the slide. The action of the four hydraulic motors 100-103 in imparting movement to the slide will be likewise equalized when the slide encounters an unsymmetrical resistance to its movement, as for example where the resistance to the action of the forming tools which are carried by the bed 13 and slide 17 is greatest at a point corresponding to one side, or one corner of the slide 17. For example, if the piston of the motor 100 should tend to move ahead of the pistons of the other motors 101-103, the piston of the said motor 100 would transmit driving force to the rock-shaft 121 through the link 143 and arm 140, the driving force of the motor 100, thereby being transmitted to the piston of the motor 101 through the rock-shaft, arm 141 and link 144; the driving force of the motor 100 which is tending to run ahead of the others, would also be transmitted to the pistons of the motors 102, 103 through arm 126 on the rock-shaft 120, the link 127, the common turning part 115, and through the common turning part to the link 124, and arm 123 on rock shaft 120, and from the arms 130, 131 on the rock shaft 120, to the links 133, 134 which are connected to the slide at points or locations adjacent the points of connection to the slide of the piston rods of the motors 102, 103. In a similar manner the tendency of any of the other hydraulic motors to run

ahead would be counteracted and the action of all of the motors on the slide equalized.

The invention may receive other embodiments than those herein specifically illustrated and described.

What is claimed is:

1. A press comprising a frame and a tool-carrying slide having a width and breadth such as would make it appreciably tilttable on its longitudinal and transverse axes, and means for reciprocating said slide and for guiding it in a straight-line; said slide reciprocating means comprising hydraulic motor-means mounted on said frame and having all together at least two movable driving parts, and driving connections between said slide, at four corners, and said movable driving parts of said hydraulic motor means; said driving connections from each of said movable driving parts of said hydraulic motor means being independent of those of the other; members extending from the driving connections, and mechanical means for equalizing the action of the movable driving parts of said hydraulic motor means, at the four corners of said slide, in imparting movement to said slide, in such manner that the slide at its four corners is maintained in substantially level planes throughout the slide movement, said mechanical equalizing means comprising a rotatable part, a part on which it turns fixed on the frame, and corresponding operating connections including links of equal effective length attached at one end thereof to said rotatable part at diametrically opposite points at equal distances from the center of the rotatable part, the opposite ends of said links being connected to said members at points in a straight line including the center of said rotatable part at one position in the operation of the press.
2. A press comprising a frame and a tool-carrying slide, and means for reciprocating said slide and for guiding it in a straight line; said slide reciprocating means comprising a pair of rock-shafts, toggles connecting said rock-shafts and slide at opposite sides, hydraulic motor means mounted on said frame and having at least two movable driving parts, and driving connections between the movable driving parts of said hydraulic motor means and said rock-shafts, said driving connections from each of said movable driving parts of said hydraulic motor means being independent of those of the other; and symmetrical mechanical means for equalizing the movements of said rock-shafts.
3. A press comprising a frame and a tool-carrying slide, and means for reciprocating said slide and for guiding it in a straight line; said slide reciprocating means comprising a pair of rock-shafts, toggles connecting said rock-shafts and slide at opposite sides, hydraulic motor means mounted on said frame and having oppositely acting driving parts arranged transversely of the press between said rock-shafts, driving connections between the driving parts of said hydraulic motor means and rock-shafts, said driving connections from each of said movable driving parts of said hydraulic motor means being independent of those of the other; and symmetrical mechanical means for equalizing the movements of the said driving parts of said hydraulic motor means and rock-shafts.
4. A press according to claim 3, wherein said frame comprises side-members and a cross-member or crown, said hydraulic motor means being supported by said crown and said crown

having transversely spaced bearings for said rock-shafts and which crown sustains in tension the driving force of the movable parts of said hydraulic motor means.

5. A press comprising a frame and a tool-carrying slide, and means for reciprocating said slide and for guiding it in a straight-line; said slide reciprocating means comprising a pair of rock-shafts, toggles connecting said rock-shafts and slide at opposite sides, hydraulic motor means mounted on said frame and having oppositely acting driving parts arranged transversely of the press between said rock-shafts, cross-heads, to which the driving parts of said hydraulic motor means are connected, and driving connections between said cross-heads and rock-shafts, said driving connections from each of said movable driving parts of said hydraulic motor means being independent of those of the other.

6. A press comprising a frame and a tool-carrying slide, and means for reciprocating said slide and for guiding it in a straight-line; said slide reciprocating means comprising a pair of rock-shafts, toggles connecting said rock-shafts and slide at opposite sides, hydraulic motor means mounted on said frame and having oppositely acting driving parts arranged transversely of the press between said rock-shafts, cross-heads to which the driving parts of said hydraulic motor means are connected, and driving connections between said cross-heads and rock-shafts, said driving connections from each of said movable driving parts of said hydraulic motor means being independent of those of the other; members extending from the driving connections and mechanical means for equalizing the movements of the driving parts of said hydraulic motor means, said mechanical equalizing means comprising a rotatable part, a part on which it turns fixed on the frame and corresponding operating connections including links of equal length attached at one end to said rotatable part at diametrically opposite points at equal distances from the center of the rotatable part, the opposite ends of said links being connected to said members at points in a straight line including the center of said rotatable part at one position in the operation of the press.

7. A press comprising a frame, a tool-carrying slide, and means for reciprocating said slide and for guiding it in a straight-line; said frame comprising side tension-members and a cross-tension-member or crown, said slide reciprocating means comprising a pair of rock-shafts mounted closely adjacent said side tension members, toggles connecting said rock-shafts and slide at opposite sides, hydraulic motor means supported by said crown between said rock-shafts and having oppositely acting driving parts parallel to the crown, and driving connections between the driving parts of said hydraulic motor means and rock-shafts.

8. A press comprising a frame and a tool-carrying slide having a width and breadth such as would make it appreciably tilttable on its longitudinal and transverse axes, means for guiding said slide in a straight-line, means for reciprocating said slide comprising hydraulic motor means mounted on said frame and having at least two movable driving parts capable, in the absence of equalizing means, of independent action on opposite sides of said slide, and mechanical means for equalizing the action of the driving parts of said hydraulic motor means while the latter is

imparting movement to said slide in such manner that the slide at its four corners is maintained in substantially level planes throughout the slide movement, said mechanical equalizing means comprising a pair of rock-shafts, a pair of spaced arms on each of said rock-shafts, links connecting said arms to said slide at four places, adjacent the four corners of the slide, a common movable part, another arm on each of said rock-shafts, a pivotal support on said frame on which said common movable part turns, and corresponding operating connections including links of equal effective length attached at one end thereof to said common movable part at diametrically opposite points at equal distances from the center thereof, the opposite ends of said

links being connected to the latter arms on said rock-shafts at points in a straight line including the center of said pivotal common movable part at one position in the operation of the press.

9. A press according to claim 8, in which the connections between the hydraulic motor means and the slide are rods on the movable parts of the hydraulic motor means attached to the slide. 5

10. A press according to claim 8, in which four hydraulic motors are employed and in which the connections between the motors and slide are rods on the movable parts of the hydraulic motors attached to the slide adjacent its four corners. 10

WILLIAM KLOCKE. 15
